UNITED STATES PATENT OFFICE.

ELIJAH CHETWYND, OF HANLEY, COUNTY OF STAFFORD, ENGLAND, AS
SIGNOR TO THOMAS H. TAYLOR, OF NEW YORK, N. Y.

DESIGN FOR AN EARTHENWARE DISH.

SPECIFICATION forming part of Design No. 15 063 dated June 17, 1884.

Application filed April 16, 1884. Term of patent 7 years.

To all whom it may concern:

Be it known that I, ELIJAH CHETWYND, a subject of the Queen of Great Britain, and a resident of Hanley, Staffordshire, England, 5 have invented and produced a new and original Design for Table-Ware, of which the following is a specification.

My invention relates, in general, to earthenware dishes, and particularly to the several 10 pieces that constitute table and toilet sets. I have selected the soup-tureen from the several pieces constituting a dinner-set, as that embodies all the novel features of my design.

Figure 1 is a side elevation of the dish and its 15 cover, and Fig. 2 is a plan of the same.

A represents the body of the dish, which is rectangular in plan, the corners being rounded and the sides and ends very slightly convex. In side elevation the body A presents a foot or base cut away at *a*, at the middle of the sides and ends, so as to leave feet *b* at the corners only, which gives a light and ornamental appearance to the base. Above this base the body expands or flares outward to a point, *c*, near its top, the outline at the corners being very slightly convex at *d* and sharply rounded at *e*, where the body is drawn in to form a contracted band, *e*. The cover B projects over or beyond the contracted portion *e* of the body, and has in plan substantially the same contour as the body A. The

cover has a beveled band, *f*, at its margin, which is joined by a rounded bead or shoulder, *g*, to the convex surface *h* of the cover. The handle C on the cover is designed to 35 represent the somewhat conventionalized branches, buds, and flower of a sunflower. In the center is a sunflower, *i*, in full bloom, and this is flanked on each side by buds *j* on short curved stems. In low relief on the cover are 40 the stems and leaves *k*. The handles D on the body A stand at an angle from the body, as shown, and present the same design. Each handle comprises the representation of a central sunflower, *i'*, flanking-buds *j'*, and stems 45 and leaves *k'* in relief on the body of the dish.

It is intended that the handles on the body and that on the cover shall present in substance the same design.

Having thus described my invention, I 50 claim—

1. The design for a dish, as described and shown.
2. In a design for a dish, the design for a handle to a cover or dish, as shown.

In witness whereof I have hereunto signed my name in the presence of two subscribing witnesses.

ELIJAH CHETWYND.
